UNITED STATES PATENT OFFICE

113,063

DESIGN FOR AN ELECTRIC FAN

James J. Gough, Chicago, Ill., assignor to Chicago Electric Manufacturing Company, Chicago, Ill., a corporation of Illinois

Application August 4, 1938, Serial No. 79,086

Term of patent 7 years

To all whom it may concern:

Be it known that I, James J. Gough, a citizen of the United States, residing at 6333 West Sixty-fifth Street, Chicago, Illinois, have invented a new, original, and ornamental Design for an Electric Fan, of which the following is a specification, reference being had to the accompanying drawing, forming a part thereof.

Figure 1 is a side elevational view of an electric fan showing my new design;

Figure 2 is a rear elevational view thereof, a portion of the guard being broken away; and

Figure 3 is a plan view of the base detached from the motor housing.

The dominant feature of my design resides in the portions illustrated in solid lines.

I claim:

The ornamental design for an electric fan, substantially as shown and described.

JAMES J. GOUGH.
